M. CAPLAN

Des. 119,356

WRAP COVER FOR CYLINDRICAL CONTAINERS

Filed Dec. 5, 1939

Inventor:
Moses Caplan,
by Harry Roth, Townsend Miller, Hirsch, Hittys.

UNITED STATES PATENT OFFICE

119,356

DESIGN FOR A WRAP COVER FOR CYLINDRICAL CONTAINERS

Moses Caplan, Boston, Mass.

Application December 5, 1939, Serial No. 88,708

Term of patent 3½ years

To all whom it may concern:

Be it known that I, Moses Caplan, a citizen of the United States, residing at Boston, in the county of Suffolk and State of Massachusetts, have invented a new, original, and ornamental Design for a Wrap Cover for Cylindrical Containers, of which the following is a specification, reference being had to the accompanying drawing, forming part thereof:

The single figure of the drawing is a plan view of the wrap cover for cylindrical containers, showing my design.

I claim:

The ornamental design for a wrap cover for cylindrical containers, substantially as shown.

MOSES CAPLAN.
